CLAIM

The ornamental design for a strap, as shown and described.

DESCRIPTION

FIG. 1 is a rear view of a strap showing my new design;

FIG. 2 is a front view thereof;

FIG. 3 is a top view thereof;

FIG. 4 is a bottom view thereof;

FIG. 5 is a left side view thereof;

FIG. 6 is a right side view thereof; and,

FIG. 7 is a perspective view thereof.

The broken lines depict stitching on the strap and form no part of the claimed design.
